UNITED STATES PATENT OFFICE.

JAMES R. MOFFATT, OF CHICAGO, ILLINOIS, ASSIGNOR TO UNION SPECIAL MACHINE COMPANY, OF CHICAGO, ILLINOIS, A CORPORATION OF ILLINOIS.

THREAD-CONTROLLING MECHANISM FOR SEWING MACHINES.

Application filed June 22, 1926. Serial No. 117,724.

The invention relates to new and useful improvements in a thread controlling mechanism for sewing machines, and more particularly to the thread controlling mechanism for the looper thread of the machine.

An object of the invention is to provide a thread controlling mechanism for a threaded looper wherein the movable parts of the thread controlling mechanism are located close to the looper and movable therewith.

A further object of the invention is to provide a thread controlling mechanism for the looper thread wherein the thread is taken up and given up by movable thread eyes mounted on the looper carrier and cooperating with a stationary member having cam faces and shoulders for properly taking up and giving up thread.

A further object of the invention is to provide a thread controlling mechanism of the above type wherein the needle guard is used for controlling the time of release of the thread by the stationary member.

A still further object of the invention is to provide a combined pull-off and clamp for the looper thread which is timed so that the looper thread is clamped between the pull-off and the looper when the looper is on the forward part of its movement so as to insure the proper control of the looper thread by the looper thread controlling mechanism, and wherein said thread clamp releases the looper thread while the looper is on the forward part of its stroke so that the thread pulled from the supply may be taken up by the looper thread controlling mechanism and the looper.

These and other objects will in part be obvious and will in part be hereinafter more fully disclosed.

In the drawings which show by way of illustration one embodiment of the invention—

Figure 1 is a view partly in front elevation and partly in section, showing more or less diagrammatically a portion of a sewing machine embodying my improvements;

Fig. 2 is a side view of the end of the work supporting arm and with the end cap removed to show the looper and thread controlling mechanism associated therewith;

Fig. 3 is an enlarged end view of the work supporting arm with the end cap removed to show the looper and the thread controlling mechanism, and also the needles;

Fig. 4 is a view similar to Fig. 3, but showing the needles all the way up and the looper at the forward end of its stroke;

Fig. 4^a is a side view of the parts shown in Fig. 4, the needles being omitted;

Fig. 5 is a view similar to Fig. 3, but showing a portion only of the end of the work support, and showing the needles all the way down and the looper at the rear end of its stroke;

Fig. 6 is a side view of the parts as shown in Fig. 5;

Fig. 7 is a view similar to Fig. 4, with a portion of the looper broken away to show in full lines the projection on the needle guard which assists in controlling the looper thread, and also one of the thread guards broken away, to show in full lines the shoulder on the stationary thread controlling cam;

Fig. 8 is a view similar to Fig. 6, but showing the looper retracted sufficiently so that the thread controlling member on the needle guard is brought close up to the stationary thread controlling cam;

Fig. 9 is a detail in perspective showing the thread fingers, thread eyes, the thread clamp constituting a thread pull-off mechanism and thread clamping device;

Fig. 10 is a view from the end of the machine showing the stationary thread cam, the thread guides, the looper carrier, the needle guard and the member carried thereby which cooperates with the stationary thread controlling cam with the looper thread retained on the upper shoulder of the controlling cam;

Fig. 11 is a view from the end of the machine showing the looper, the thread guides and the stationary thread controlling cam with the looper thread carried into engagement with the under surface of the eccentric portion of the thread controlling cam;

Fig. 12 is a plan view of a portion of the overhanging arm, the needle lever, and the device for clamping and pulling off the looper thread, and

Fig. 13 is a sectional view through the overhanging arm and the needle lever, showing the thread clamping and pull-off device in elevation.

The invention is directed broadly to a looper thread controlling mechanism, and consists in the arrangement of the movable parts of the thread controlling mechanism very close to the looper so that the control of the looper thread is very close to the stitching point.

This enables threads to be used which are very loosely twisted, and liable to stretch or tear apart, and yet perfect stitching made. In carrying out the invention, a stationary 5 thread cam is used which is located alongside of the looper and attached to the end of the work supporting arm. Associated with this stationary cam, are thread eyes which are mounted on the looper carrier. These eyes 10 are so disposed on the carrier, and the stationary thread cam is so disposed relative to the carrier, that one eye is on one side of the stationary thread cam, while the other is on the other side of the stationary thread cam. 15 Therefore, the thread running between the thread eyes will be caused to engage the stationary thread cam and moved along the same. The thread from the supply is led through a guiding tube, which is arranged on 20 the work supporting arm so that the point of delivery of the thread to these movable thread eyes associated with the looper, is midway between the rear end of the stroke of the thread eyes and the forward end of the 25 stroke of the thread eyes. The stationary thread cam is provided with a shoulder, so that the thread passing between the thread eyes engages said shoulder as the looper moves forward to enter the needle thread loop. At 30 this time, the thread eyes are approaching the thread supply tube, but the engagement of the thread with the shoulder on the stationary controlling cam, takes up all the slack in the looper thread and pulls the slack in 35 the looper thread back through the eye of the looper as the looper moves forward. This prevents any possible kinking or buckling of the looper thread between the eye thereof and the material which is liable to push the thread 40 loop to one side and cause the skipping or malformation of stitches. This stationary thread cam has a clearance space into which the thread passes after it leaves the shoulder thereon. Said stationary thread controlling 45 cam has an eccentric curved surface against which the thread is carried by the thread eyes as the looper approaches the forward end of its stroke, and this is for the purpose of drawing from the pull-off the thread which 50 is drawn off from the supply on the first part of the forward movement of the looper. The pull-off has means associated therewith for clamping the thread between the active finger for pulling the thread from the supply 55 and the looper; and this clamping means is active during the first part of the forward movement of the looper, but the clamp is released during the latter part of the stroke of the looper and at the time when the thread 60 is carried against this eccentric surface of the stationary thread controlling cam. This stationary thread controlling cam has another shoulder which is so associated with the movable thread eyes, that the looper thread ex- 65 tending between the thread eyes will be

snapped in front of the shoulder as the looper reaches the forward end of its stroke. As the looper starts on its backward movement, the thread is carried against this forward shoulder and slack in the looper thread taken up 70 so that the looper thread is properly positioned for the needle to enter the thread triangle forming the looper thread loop. The controlling member on the needle guard becomes active at this time to prevent the thread from slipping from said forward shoulder until the needle is well down into the thread triangle, after which the looper thread is permitted to become disengaged from the forward thread shoulder. 75

Referring more in detail to the drawings, my improved thread controlling mechanism is shown as applied to a sewing machine having an overhanging arm 1 carried by a suitable standard 2. Mounted in the overhanging arm 1 is a needle bar 3, carrying, as shown in the present embodiment of the invention, three needles, indicated at 4. Cooperating with the three needles is a looper 5. This looper 5 is adapted to cooperate with all three 80 needles, entering first the needle thread loop of the left-hand needle as viewed in Fig. 3, then the middle needle, and finally the right-hand needle, and the needles are set at different heights in order to insure the proper timing of the looper and the needles so that the looper will enter all three needle thread loops. The looper 5 is mounted in a looper carrier 6, and the looper carrier 6 is rigidly secured to a looper shaft 7. The looper shaft 7 is mounted in a work supporting arm 8, and extends lengthwise thereof. Suitable means is provided for oscillating the looper shaft 7 so as to move the looper into and out of the needle thread loops, and also for moving the 90 looper shaft endwise for giving a needle avoiding movement to the looper. The material being stitched is fed off from the end of the work supporting arm, and therefore, the looper moves back and forth in a plane 95 at right angles to the line of feed. The needle bar is reciprocated by means of a needle lever 100 9 of the usual construction.

Mounted on the looper is a needle guard 10. This needle guard, so far as its relation to the looper is concerned, and as to its function as a needle guard, is of the well-known construction. Said needle guard is provided, however, with a projecting member 11 which functions in connection with the thread controlling mechanism as will be hereinafter more fully disclosed. The looper thread is led from the supply through suitable tensions and thence to a thread slot 12 in an arm 13 secured to the needle lever 9 by means of a screw 14 passing through a slot 15 in the arm 13. The thread after passing through this slot 12, is then led through a thread eye 16 in an arm 17 carried by a bracket 18. The bracket 18 is secured by a screw 19 to the overhanging 130

arm 1. The screw 19 passes through an elongated slot 20 in the bracket 18. The looper thread after leaving the eye 16 passes in rear of the arm 21, thence through a slot 22 in a bar 23 attached to the bracket 18. Mounted on the arm 13 is a clamping finger 24, which slides beneath the bar 23 and engages and clamps the looper thread which passes through the slot 22. The looper thread after leaving the thread clamp passes through a thread guide 25, and thence to a thread guiding tube 26. This thread guiding tube 26 extends along the frame to the work supporting arm 8, and along the work supporting arm 8 to the end thereof. The thread passes from the thread guiding tube 26 to a thread guide 27 mounted on the looper carrier 6, and thence to a thread guide 28 also mounted on the looper carrier 6. After leaving the thread guide 28, said looper thread passes to the eye 29 at the heel of the looper and then to the eye 30 at the point of the looper. These thread guides 27 and 28 oscillate with the looper as they are mounted on the looper carrier. They are spaced from each other as clearly shown in the drawings, and between the thread guides is a stationary thread controlling cam 31. This stationary thread controlling cam 31 is secured by means of a screw 32 to a lug 33 attached to the work supporting arm 8 of the machine. The stationary thread controlling cam is provided with a shoulder 34 which will be referred to hereinafter as the rear shoulder of the stationary thread controlling cam. It is also provided with a shoulder 35 which will be referred to as the forward shoulder of the stationary thread controlling cam. Between these shoulders 34 and 35, the stationary cam is cut away to form a clearance space. The under face 36 of the stationary thread controlling cam 31 is curved and the curvature is eccentric to the axis of oscillation of the looper, and this eccentric surface is so set relative to the thread guides 27 and 28 that the thread is free from contact with said surface until the looper approaches the forward end of its stroke.

This stationary thread controlling cam is so positioned relative to the needle guard associated with the looper, that when the looper moves laterally to avoid the needle, the member 11 on the needle guard will be brought close up to the stationary thread controlling cam as shown in Fig. 8 of the drawings. This member 11 is for the purpose of aiding in retaining the looper thread on the forward shoulder 35 of the stationary thread controlling cam.

When the looper is at the rear end of its stroke, the thread guides 27 and 28 are so positioned that the looper thread passing between said thread guides is below the shoulder 34. The thread guides are also some distance below the extreme end of the thread guiding tube 26. As the looper moves for-

ward, the looper thread will be brought into contact with the shoulder 34, and this shoulder cooperating with the movable thread guides will cause all of the slack thread formed by the forward movement of the looper to be taken up and the looper thread drawn back through the eye of the looper. Thus it is that the slack is taken out of the looper thread, and there is no liability of the looper thread buckling as the point of the looper approaches the needle thread loop. If such buckling of the looper thread occurs, it is apt to push the needle thread loops to one side, and thus cause a skipping of stitches. The shaping of the shoulder 34 is such that when the looper point has entered the needle thread loop or loops, provided a plurality of needles are used, and the eye of the looper is approximately opposite the first needle, the looper thread is drawn off from said shoulder so that the looper thread is slack, and thus it is that looper thread is given up to the looper as it forms its own loop through the needle thread loops into which it has entered. When the looper thread is dropped from the shoulder 34, it enters the clearance space beneath a curved surface 36 of the stationary thread controlling cam. Before the looper reaches the end of its forward stroke, however, the thread between the thread guides 27 and 28 will be carried against the portion of the curved surface 36 adjacent the shoulder 35. The purpose of this contact of the looper thread with the edge of the stationary member is to aid in the pulling of the looper thread from the supply of thread provided by the pull-off, and furthermore, to aid in insuring that there will be sufficient tension on the looper thread to cause it to snap in front of the shoulder 35 on the stationary thread controlling member.

In Figures 5 and 6 of the drawings, the looper is at the rear end of its stroke, and the looper thread is about to be placed against the shoulder 34.

In Figures 4, 4^a, 7 and 8 of the drawings, the looper thread is against the shoulder 35. This shoulder 35 on the stationary thread controlling cam operates to hold the looper thread when the looper is retracted. This is for the purpose of taking up the slack in the looper thread as the looper moves back and moves laterally so as to provide a thread triangle into which the needles will enter with certainty. In order to insure that the looper thread will be held on the shoulder 35 until the points of the needles are well down into the thread triangle, the member 11 of the needle guard during the lateral movement of the looper comes right up close to the side face of the stationary thread controlling cam as shown in Fig. 10. When, however, the needles are well down into the looper thread loop or thread triangle, then this member 11 will have moved back away from the shoulder 35, a sufficient distance so as to permit the

looper thread to slide therefrom. When, however, the needle guard moves laterally, and the looper thread is entirely released from any control thereby, said looper thread will be 5 drawn taut between the thread guides 27 and 28 by reason of the fact that these thread guides will then be moving away from the thread guiding tube 26. This drawing of the thread taut at this time has little or no effect 10 upon the stitch formation, but it does position the looper thread so that it can be properly drawn against the shoulder 34 when the looper starts on its forward movement.

In Fig. 10 I have shown the position of the 15 member on the needle guard relative to the stationary thread cam which aids in the holding of the looper thread on the upper shoulder 35 of the stationary thread controlling cam. The looper is on its retracting movement and 20 the needle guard is, therefore, moving in the direction of the arrow in this figure, and will soon reach a point where the thread will be drawn off from the shoulder, due to the fact that the thread guides are moving away from 25 this shoulder and the member on the needle guard is uncovering the shoulder.

In Fig. 11 of the drawings, I have shown the looper well toward the forward end of its stroke, and the looper thread carried against 30 the under face 36 of the stationary thread controlling cam, so that the slack is taken out of the looper thread and the looper thread made sufficiently taut so as to snap around in front of the shoulder 35.

35 The looper thread is indicated at 1 in the drawings. In Figures 12 and 13 I have shown a little more clearly the manner whereby the arm 24 clamps the looper thread. This arm 24 moves directly beneath the bar 23 and 40 will move the thread along the slot 22 until the thread is brought against the end of the slot, and thus the thread is clamped. This clamping of the thread occurs when the needles are 45 on the lower part of their down stroke, and at this time, the looper is retracted and is about to move forward into the needle thread loops. While the looper thread is clamped by the arm 24, the arms 13 and 21 moving away from the thread guide 16 and the slot 22 after 50 the looper thread is clamped, will draw thread from the supply, and this thread is given up when the needle clamp is open, so that the thread guides associated with the looper may draw the thread through and supply the same to the looper.

55 It will be noted from the above description that I have provided a thread controlling mechanism for a looper thread wherein the thread passes directly from said thread controlling mechanism to the looper without engaging any thread guides whatever. It will also be noted that the thread guiding tube 26 terminates substantially at the end of the work supporting arm and that the looper and the thread controlling mechanism for the

looper thread are all located beyond the end of the work supporting arm.

The machine is particularly adapted for use in connection with a plurality of needles, and a covering thread which is laid back and forth in front of the needles by a thread laying device of the usual type. This covering thread is indicated at *c* in the drawings. Said covering thread passes through a slot 12^a in the arm 13, thence through a guide eye 16^a, then behind the arm 21, and thence through a thread guiding eye 16^b. This covering thread is not clamped, but the arm 21 does pull the thread from the supply.

While I have shown and described the invention as applied to a machine having a plurality of needles, it will be understood that a single needle could be used with just as much advantage. The thread controlling mechanism is especially useful in a multiple needle machine wherein the looper enters all of the needle loops, as the thread controlling mechanism is closely positioned relative to the looper and will much more quickly and efficiently handle the slack thread.

While I have shown my improvement as applied to a machine having a work supporting arm wherein the material is fed from the end of the arm, it will be understood that it can also be used equally as well with a flat bed machine. Then again, while I have shown the invention as applied to a machine wherein the looper moves in a plane at right angles to the line of feed, it will be understood that the looper may be otherwise disposed relative to the line of feed. In the particular type of machine illustrated, the looper supporting shaft extends beyond the end of the arm, and the entire thread controlling mechanism associated with the looper, exclusive of the looper thread clamp and pull-off, is beyond the end of the looper supporting arm.

It is obvious that minor changes in the details of construction and the arrangement of the parts may be made without departing from the spirit of the invention as set forth in the appended claims.

Having thus described the invention, what I claim as new and desire to secure by Letters Patent, is—

1. In a sewing machine, the combination of a looper carrier, a looper mounted thereon, a thread controlling mechanism for said looper including a stationary cam member, and a movable member mounted on the looper carrier adjacent the looper and cooperating with said stationary member.

2. In a sewing machine, the combination of a looper carrier, a looper mounted thereon, a thread controlling mechanism for said looper including a stationary cam member, and movable thread guides mounted on the looper carrier adjacent the looper and cooperating with said stationary cam member.

3. In a sewing machine, the combination

- of a looper carrier, a looper mounted thereon, a thread controlling mechanism for said looper including a stationary cam member, and movable thread guides mounted on the 5 looper carrier adjacent the looper and cooperating with said stationary cam member, said stationary cam member having a shoulder against which the thread between the thread guides is carried during the 10 oscillation of the carrier for taking up the thread on the first part of the forward movement of the looper.
4. In a sewing machine, the combination of a looper carrier, a looper mounted thereon, a thread controlling mechanism for said looper including a stationary cam member, and movable thread guides mounted on the 15 looper carrier adjacent the looper and cooperating with said stationary cam member, said stationary cam member having a shoulder for engaging the thread between the thread guides for taking up the looper thread on the first part of the backward movement of the looper.
- 20 5. In a sewing machine, the combination of a looper carrier, a looper mounted thereon, a thread controlling mechanism for said looper including a stationary cam member, movable thread guides mounted on the looper 25 carrier and cooperating with said stationary cam member, said stationary cam member having a shoulder for engaging the thread between the thread guides for taking up the looper thread on the first part of the backward 30 movement of the looper, a needle guard mounted on the looper carrier and having a projecting member adapted to move close up to the stationary thread controlling cam for holding the looper thread on said 35 shoulder.
- 40 6. In a sewing machine, the combination of a looper carrier, a looper mounted thereon, a thread controlling mechanism for said looper including a stationary cam member, movable thread guides mounted on the looper 45 carrier adjacent the looper and cooperating with said stationary cam member, said stationary cam member having a shoulder against which the looper thread is carried by said thread guides for taking up the thread on the first part of the forward movement 50 of the looper, and a shoulder for engaging the looper thread for taking up the thread on the first part of the backward movement of the looper.
- 55 7. In a sewing machine, the combination of a looper carrier, a looper mounted thereon, a thread controlling mechanism for said looper including a stationary cam member, movable thread guides mounted on the looper 60 carrier and cooperating with said stationary cam member, said stationary cam member having a shoulder against which the looper thread is carried by said thread guides for taking up the thread on the first part of the forward movement of the looper.
- 65 forward movement of the looper, a shoulder for engaging the looper thread for taking up the thread on the first part of the backward movement of the looper, said stationary cam member being cut away between said shoulders to form a clearance space, and an eccentric surface so that the thread after leaving the first-named shoulder passes into the clearance space and gives slack to the looper, and so that the looper thread is carried by the thread guides against said eccentric surface for taking the slack from the looper thread as the looper approaches the forward end of its stroke. 70
8. In a sewing machine, the combination of a work supporting arm, a looper shaft mounted in said arm and projecting beyond the end thereof, a looper carrier mounted on the end of said shaft, spaced thread guides mounted on said looper carrier, a stationary thread cam mounted on the end of said arm and located between said thread guides, said thread guides and said stationary cam member cooperating to take up the looper thread on the first part of the forward movement 80 of the looper, then give slack to the looper as it moves into the needle thread loop, then take the slack from the looper thread as it approaches the forward end of its stroke, and then to take up the looper thread on the 85 first part of its retracting movement.
9. In a sewing machine, the combination of a work supporting arm, a looper shaft mounted in said arm and projecting beyond the end thereof, a looper carrier mounted on said shaft, a thread carrying looper mounted on said carrier, spaced thread guides mounted on said looper carrier adjacent the looper, and a stationary thread cam carried by the outer end of said work supporting arm and disposed between said thread guides and cooperating with said thread guides for controlling the looper thread during the forward and backward movement of the looper. 90
10. In a sewing machine, the combination of a work supporting arm, a looper shaft mounted in said work supporting arm, a looper carrier mounted on said shaft, a thread carrying looper mounted in said carrier, a thread guiding tube mounted on said work supporting arm and terminating at the end thereof, a thread controlling mechanism disposed at the end of the work supporting arm and operating upon the thread between the end of said tube and the eyes of said looper for controlling the looper thread, said thread controlling mechanism including spaced thread guides mounted on the looper carrier adjacent the looper, and a stationary cam mounted on the end of the work supporting arm and located between said thread guides. 100
11. In a sewing machine, the combination of a work supporting arm, a looper shaft mounted in said work supporting arm, a 105

looper carrier mounted on said shaft, a thread carrying looper mounted in said carrier, a thread guiding tube mounted on said work supporting arm and terminating at the 5 end thereof, a thread controlling mechanism disposed at the end of the work supporting arm and operating upon the thread between the end of said tube and the eyes of said looper for controlling the looper thread, said 10 thread controlling mechanism including spaced thread guides mounted on the looper carrier, and a stationary cam mounted on the end of the work supporting arm and located between said thread guides, said stationary 15 cam having spaced thread engaging shoulders and cut away between said shoulders so as to form a clearance space for the looper thread after leaving one shoulder before it is brought into engagement with the other. 20 12. In a sewing machine, the combination of a work supporting arm, a looper shaft mounted in said work supporting arm, a looper carrier mounted on said shaft, a thread carrying looper mounted in said

carrier, a thread guiding tube mounted on 25 said work supporting arm and terminating at the end thereof, a thread controlling mechanism disposed at the end of the work supporting arm and operating upon the thread between the end of said tube and the 30 eyes of said looper for controlling the looper thread, said thread controlling mechanism including spaced thread guides mounted on the looper carrier, a stationary cam mounted on the end of the work supporting arm and 35 located between said thread guides, said stationary cam having spaced thread engaging shoulders and cut away between said shoulders so as to form a clearance space for the looper thread after leaving one shoulder before it is brought into engagement with the other, and a member mounted on said looper carrier and cooperating with said stationary cam for retaining the looper thread on one of 40 said shoulders. 45

In testimony whereof, I affix my signature.

JAMES R. MOFFATT.
